UNITED STATES PATENT OFFICE.

ALBERT M. WOLTZ, OF BALTIMORE, MARYLAND, ASSIGNOR, BY MESNE ASSIGNMENTS,
TO SAMUEL D. YOUNG, TRUSTEE, OF GRAND RAPIDS, MICHIGAN.

DISPLAY RACK.

Application filed October 4, 1921. Serial No. 505,251.

This invention is a device for supporting umbrellas, parasols and the like, for display purposes.

It is the practice in some mercantile establishments, to provide racks for umbrellas, parasols and the like, which are constructed with an inclined base member having holes therein, into which are fitted bushings, through which the articles to be displayed are thrust. The bushings are made of a diameter small enough to engage a rolled umbrella with considerable friction, in order that it may be retained against accidental displacement, and substantially evenly spaced to make an attractive display. One of the disadvantages of this arrangement is that the repeated insertion and removal of the umbrella or parasol, by the salesman, causes the fabric to rub against the bushing, soon resulting in imparting a shopworn appearance, and in fact frequently damaging the article.

One of the objects of the invention is to provide a display device, by means of which umbrellas and the like, may be supported with their handles in stepped relation, by a means which will engage only the ferrule end of the stick, and thereby avoid friction and all rubbing action against the fabric forming the covers. A further object is to provide a device in which the article engaging elements are adjustable, to receive umbrella and parasol sticks or ferrules of different thicknesses.

The invention will be hereinafter fully set forth and particularly pointed out in the claims.

In the accompanying drawing:—

Figure 1 is a side elevation illustrating a display rack constructed in accordance with the invention, parts being broken away and shown in section, the case or cabinet being diagrammatically indicated. Figure 2 is a top plan view, parts being broken away and shown in section.

Referring to the drawing, the articles to be displayed are preferably enclosed within a case or cabinet, constructed with a base 10, side walls 11, and a back wall 12, connected by a suitable top (not shown), and closed at the front by movable doors, in a manner well-known in the art.

The article supporting portions of the cabinet are mounted between spaced apart stringers 13, disposed in an inclined posi-

tion within the case or cabinet, the lower ends being located at the front. Interposed between and secured to the stringers 13, are spaced-apart risers 14, arranged in stepped relation, as clearly shown in Figure 1. Secured to each riser is a set of blocks 15, arranged between the stringers, the blocks of each set being separated transversely by spaces 16.

Extending transversely under the blocks 15 of the respective sets, and secured to the risers 14, are supporting strips 17, bridging the spaces 16, to each of which is secured a series of spring arms 18, one for each space 16. It will be noted that the supporting strips are somewhat narrower than the blocks 15, and form the bottoms of receptacles produced by the spaces between the blocks 16 and risers 14. Each spring arm 18 is secured at its lower end to a supporting strip 17, the upper end being free and provided with a gripping portion 19. Said gripping portion may be an approximately semicircular member, of a width which will permit it to freely move in the space 16, within which it is located. The tension of the spring arm 18 is such that the gripping member 19 will normally press against the contiguous riser 14. By so shaping the members 19 a minimum bearing surface 85 upon the article to be gripped is provided. It is preferred to provide the risers with longitudinal grooves 20, disposed opposite to the spring arms 18, and gripping members 19, said grooves being shaped to accommodate the ferrule end of an umbrella or parasol stick, as clearly shown in Figure 2, to prevent lateral displacement of the article when its end is engaged by the gripping member 19. In order to provide a finish to the device, the blocks 15 and the upper edges of the risers 14 are covered by tread pieces 21, which are provided with openings 22, through which the ends of the umbrella sticks may be inserted. These openings are 100 preferably surrounded by finishing bushings 23.

In practice, the receptacles formed by the spaces 16 are of a depth which does not exceed the usual length of the ferrule end of an umbrella stick, or the like. The article is supported in the display rack, by inserting its ferrule end through one of the openings 22, until it engages the convex portion of the gripping member 19, forcing the same 110

back against the tension of its spring arm 18. The umbrella is forced in until its end rests upon the supporting strip 17, and the gripping member 19 will force it into the groove 20, so as to clamp it firmly and hold it against lateral displacement. The tension of the spring arms 18 is sufficient to grip the end of the umbrella stick, with such force as to hold the umbrella in a perfectly vertical position, thereby insuring an exceedingly neat appearance of the articles on display, with substantially all of each article presented in view, and all of them maintained in approximate parallelism. Thus the customer has ample opportunity to inspect the articles without necessitating frequent handling, and an attractive display is assured. When it is desired to remove the umbrella, it is only necessary to pull upwardly thereupon, and the gripping member will yield sufficiently to permit of its withdrawal. In order to prevent marring of the umbrella sticks the gripping members 19 are covered with a suitable non-abrading substance. The convexity of the members 19 aids in guiding the umbrella stick into position as it is inserted, and insures a firm gripping with a minimum bearing surface in contact with the said stick.

From the foregoing, it will be readily understood that the invention provides an inexpensive display device, by means of which umbrellas and the like may be supported in stepped relation, and in parallelism, with the covers entirely exposed to view. A further advantage is that the articles are supported in such manner, that the covers will not be subjected to friction or rubbing, in inserting them into the rack and removing them therefrom. An important advantage is that the device is so constructed, that the various gripping devices will accommodate themselves to umbrella sticks of different thicknesses, without necessitating previous adjustment.

Having thus explained the nature of the invention and described an operative manner of constructing and using the same, although without attempting to set forth all of the forms in which it may be made, or all of the forms of its use, what is claimed is:—

1. A display rack of the character described comprising means providing a plurality of receptacles supported in stepped relation, said receptacles being of a depth corresponding to the approximate length of the ferrule end of a standard umbrella or parasol, spring arms mounted in the bottom portions of the respective receptacles, and gripping members carried by said arms.

2. A display rack of the character described comprising means providing a plurality of receptacles each of a depth corresponding to the approximate length of the ferrule end of a standard umbrella or para-

sol, supporting means in the bottoms of the respective receptacles, spring arms attached at one end to said supporting means, and gripping members carried by the free ends of said arms.

70

3. A display rack of the character described comprising spaced apart inclined stringers, means supported by said stringers providing a plurality of receptacles each of a depth corresponding to the approximate length of the ferrule end of a standard umbrella or parasol, and gripping devices located in the respective receptacles.

75

4. A display rack of the character described comprising spaced-apart stringers, spaced apart risers secured to said stringers, means carried by the risers and cooperating therewith to provide a plurality of receptacles each of a depth corresponding to the approximate length of the ferrule end of a standard umbrella or parasol, and gripping devices in the respective receptacles.

80

5. A display rack of the character described comprising spaced apart stringers, spaced apart risers secured to said stringers, means supported by the risers providing a plurality of receptacles, gripping devices in the respective receptacles, and means carried by the risers for supporting said gripping devices.

85

6. A display rack of the character described comprising spaced apart stringers, spaced apart risers secured to said stringers, means secured to said risers providing a plurality of receptacles, supporting strips carried by the risers and extending beneath the receptacles, and gripping devices located in the receptacles and secured to said supporting strips.

90

7. A display rack of the character described comprising spaced apart stringers, spaced apart risers secured to said stringers, means secured to said risers providing a plurality of receptacles, supporting strips carried by the risers and extending beneath the receptacles, spring arms secured at one end to said supporting strips and gripping devices secured to the free ends of said spring arms.

100

8. A display rack of the character described comprising means providing a plurality of receptacles in stepped relation, each receptacle being of a depth corresponding to the approximate length of the ferrule end of a standard umbrella or parasol, and yieldably-supported convex gripping devices in the respective receptacles, each of said receptacles having one wall provided with a groove parallel with and cooperating with a contiguous gripping device.

115

9. A display rack of the character described comprising a plurality of blocks, means supporting said blocks in spaced relation, supporting strips extending beneath the blocks and crossing the spaces between

120

125

130

- them, and gripping devices in the spaces between the blocks and supported by said strips.
10. A display rack of the character described comprising a plurality of blocks, risers supporting said blocks in spaced relation, means supporting said risers, strips secured to said risers and extending beneath said blocks, and gripping devices in the spaces between the blocks and secured to said strips.
11. A display rack of the character described comprising a riser, means supporting the same, blocks secured to said riser in spaced relation, gripping devices located in the spaces between the blocks, and a tread member covering said blocks and having openings registering with said spaces.
12. A display rack of the character described comprising inclined stringers, spaced apart risers secured to said stringers in spaced relation, blocks secured to each riser in spaced relation transversely of the rack, and gripping devices in the spaces between said blocks.
13. A display rack of the character described comprising inclined stringers, spaced apart risers secured to said stringers in spaced relation, blocks secured to each riser in spaced relation transversely of the rack, supporting strips secured to the risers and
- extending beneath said blocks, and gripping devices secured to said supporting strips and located in the spaces between said blocks.
14. A display rack of the character described comprising inclined stringers, spaced apart risers secured to said stringers in spaced relation, blocks secured to each riser in spaced relation transversely of the rack, supporting strips secured to the risers and 35 extending beneath said blocks, gripping devices secured to said supporting strips and located in the spaces between said blocks, and tread pieces covering said blocks and having openings registering with said 40 spaces.
15. A display rack of the character described comprising inclined stringers, spaced apart risers secured to said stringers in spaced relation, blocks secured to each riser 50 in spaced relation transversely of the rack, supporting strips secured to the risers and extending beneath said blocks, spring arms secured at one end to said strips and located in the spaces between the blocks, gripping 55 devices carried by the free ends of said spring arms, and tread pieces covering the blocks and having openings in register with said recesses.

In testimony whereof I have hereunto set 60 my hand.

ALBERT M. WOLTZ.
